Primary Examiner — Susan Bennett Hattan*Assistant Examiner* — Leanne Was(74) *Attorney, Agent, or Firm* — Dunlap Codding, P.C.(57) **CLAIM**

The ornamental design for a lid and spoon assembly, as shown and described.

DESCRIPTION

FIG. 1 is a top plan view of a lid and spoon assembly showing our new design.

FIG. 2 is a bottom plan view thereof.

FIG. 3 is a side view thereof, the right side being a mirror image.

FIG. 4 is a cross-sectional side view thereof; and,

FIG. 5 is a bottom perspective view thereof.

Background features may be shown in broken lines for illustrative purposes only and form no part of the claimed design.
